UNITED STATES PATENT OFFICE.

FRANCIS V. PHILLIPS, OF CHICAGO, ILLINOIS, ASSIGNOR TO GEORGE H. DAYTON, OF SAME PLACE.

DOOR-CHECK.

SPECIFICATION forming part of Letters Patent No. 251,732, dated January 3, 1882.

Application filed August 23, 1880. (Model.)

To all whom it may concern:

Be it known that I, FRANCIS V. PHILLIPS, of Chicago, State of Illinois, have invented certain new and useful improvements in Door Checks; and I do hereby declare that the following is a full, clear, and exact description thereof, reference being had to the accompanying drawings, and to the letters of reference marked thereon, which form a part of this specification.

This invention relates to door-checks; and it consists in the several novel features of construction hereinafter set forth, and pointed out in the claims.

The door-check herein described and claimed operates not only to check the door slightly open, as is common with door-checks, but it may also be made at will to hold the door from closing, and is adapted to fasten the door closed.

In the accompanying drawings, Figure 1 is a perspective view of the check as it appears when the door is closed and when used to fasten the door in this position. Fig. 2 is a perspective view of the door open to the length of the check-link. Fig. 3 shows the check-link pendent on the door-frame. Fig. 4 is a central horizontal section of the complete device in the position shown in Fig. 1. Fig. 5 is a central horizontal section of the parts applied to the door, and of the outer end of the link when the door is ajar and is held from movement in either direction. Figs. 6, 7, 8, 9, and 10 are detail views.

A is the door, and B is the door-frame.

C is a metal casing, about half an inch deep, containing the mechanism permanently applied to the door.

C' is a boss applied to the frame B, flush with the case C, and having the check-link L, pivoted thereto by means of a hook, E', on the boss and eye e on the link. The link L is slotted at S, and engages the door by means of a turn-pin, T, secured to the door by means of the case C. An especially novel feature in the turn-pin T is that it may be slid backward and forward to and from the edge of the door in the slot D of the case C with a movement over the corner or front edge of the case C, so as to serve, when at the door-edge, as a T, by which to hold

the check-link and arrest the door, and when slid inward away from the door-edge to serve as a turn-pin fastening, adapted to hold the check-link against the case C, and thus secure the door closed. To these ends said turn-pin is of peculiar construction, which will be presently explained.

I is a horizontally-sliding catch, held loosely in place on the door by the case C, beneath which it is centrally placed. Its inner and exposed end is upturned to afford hold for the thumb and finger for the purpose of working it, as seen clearly in Figs. 2, 4, and 5, and its throw is limited by the screw j, which passes through the slot i in the slide. Said slide is intended to engage with the notch N in the link L when the door is opened the length of the check-link, and operates to hold the door from closing. The notch N is clearly shown in Figs. 3, 4, and 5, and in the last figure mentioned the slide I is engaged with said notch, as described. The slide I also serves as a bottom plate, on which the turn-pin T runs, and it has a rib, r, on its outer face, which fits in a groove, g, on the under face of the turn-pin, which rib, so far as it extends in the movement of the turn-pin, holds the latter from rotation.

The turn-pin T consists of the external thumb-head, the standard or shank t², the lateral arms t, and the rear projection, t'. The slot D of the case C, in which the shank t² runs, extends down the front face of the case, as shown in Fig. 10, so that the turn-pin may tilt into the position shown in Figs. 2 and 5. When it so tilts the projection t' protrudes from the slot D, as shown in said figures, and by such protrusion holds the turn-pin from rotation at this point. The rib r similarly holds it from rotation until moved to the rear of the slot D, where it is clear of the rib, and may turn in order to be released from the check-link L. If, however, it is desired to lock the turn-pin at this point to prevent its turning, (as when the turn-pin is used to hold the link L as a fastening of the closed door,) it can be so locked by pushing in the slide I, so that the lugs b b, cast on the slide, pass one to each side of the rear projection, t', of the turn-pin and prevent its rotation. The link L is provided with a projecting corner, a, which, when the link is thrown

off the turn-pin and falls pendent from the hook E', sets up under said hook and prevents the link from swinging outward in the way of the door.

5 The boss C' is of peculiar construction. It consists of the hollow rising part, tapering toward the top, and the cap-plate c'. The hook E' is cast as an extension on the inner wall of the boss, and, as it overhangs the aperture of 10 the shell, draws readily from the sand. The cap c' at its inner edge sets up against the hook E', and has a small flange, c², on its under face, which drops close inside the outer wall of the boss, as seen in Fig. 4. The link being first applied to the hook E', the cap c' is inserted beneath the hook. The parts are then fastened to the door-frame by screws passing inward through the cap c', as shown, and all the parts are thus held permanently in place on the door-frame.

15 It has been found that by reason of the molding usually present on the frames of doors it is necessary to pivot the link to a raised part or boss, and to correspondingly elevate the 20 T-fastening on the door. When this is done a stationary T-piece to engage the link projects so far as to be seriously in the way. This fault is remedied in the construction herein shown, 25 wherein the turn-pin is at the edge of the door only when the link L is engaged therewith, and when, therefore, it is harmless. At all other 30 times the turn-pin is retracted from the door-edge.

35 Having thus described my invention, I claim—

1. The combination of the check link or bar L, pivoted to the door-frame, the case or plate C, secured to the door, and the turn-pin or catch T, held movably to the door by means of the 40 case C, said turn-pin T being adapted to engage the link or bar L, and to be moved, while thus engaged, inwardly from and outwardly to the edge of the door, so as to co-operate with

the bar L to check the door when ajar, and to form therewith a fastening to the closed door, 45 substantially as described.

2. In combination with a rigid check link or bar, L, having a notch or shoulder, N, and a suitable catch, T, on the door, arranged to engage with said link or bar to check the door 50 ajar, the sliding latch I, adapted to be engaged at will with the shoulder N of the link L, so as to hold the door from closing, substantially as described.

3. In combination with the slotted link or bar 55 L, the turn-pin T, secured movably to the door by means which permit the turn-pin to slide inward from and outward to the edge of the door, and to rotate to receive or release the link only when receded, substantially as described. 60

4. In a door-check, the slotted link L, pivoted to the boss C' on the door-frame, the case C, having the slot D, the turn-pin T, having projections t and t' and the groove g, and the bottom plate, I, provided with the rib r, combined 65 and operating substantially as described.

5. In combination, the slotted link L, pivoted to the door-frame, the retaining-case C on the door, the rotating turn-pin T, held by the case C, and slide I, having the lugs b b, whereby the 70 turn-pin may be secured from rotation when operating with the link L as a fastening for the closed door, substantially as described.

6. The link L, pivoted to the door-frame by 75 the hook E' and eye e, and constructed with the corner-projections a, which bear against the hook E' to prevent the link from swinging in the way of the door, substantially as described.

In testimony that I claim the foregoing as my invention I affix my signature in presence of 80 two witnesses.

FRANCIS V. PHILLIPS.
